Specification of Letters Patent. Patented May 23, 1916.

Application filed October 10, 1913. Serial No. 794,425.

To all whom it may concern:

Be it known that I, DANA EDSON PERKINS, a citizen of the United States, and resident of Medford, in the county of Middlesex and State of Massachusetts, have invented certain new and useful Improvements in Turbines, of which the following is a specification.

The present invention relates to turbines 10 designed and adapted particularly to be driven by a flowing column of water, although the principles of the invention are applicable to turbines adapted to be driven by other motive fluids. The embodiment of 15 the invention illustrated in the accompanying drawings and hereinafter described in detail is designed primarily for use as a water turbine, and is accordingly so described, and in the following particular description the motive fluid is referred to throughout as being water. I desire, however, to say at the outset that I do not intend such particular description to be taken as a limitation of the invention, but that on 20 the contrary I intend the machine or motor herein illustrated to be understood as representing one possible embodiment of the invention and that the machine is adapted, without departure from its essential principles to be driven by other motive fluids than 25 water or to serve other purposes than that of a power generator.

The objects of my invention are generally to provide an improved form of turbine 30 which will convert a greater proportion of the potential energy existing in a head of water into useful work with a smaller percentage of loss, than has ever been done before; to provide a self-contained and compact turbine of which the rotating parts are 35 supported with means for preventing friction and wear; and to provide other improvements by which advantageous results in respect to construction and operation of 40 the turbine are secured, as will hereinafter be more fully and at large appear.

The manner in which I accomplish the foregoing objects and others hereinafter described, is set forth in the following detailed 45 description and illustrated in the accompanying drawings, to which reference is hereby made.

In the accompanying drawings, Figure 1 is a side elevation of a water turbine constructed in accordance with the principles of

the present invention. Fig. 2 is a vertical sectional view taken on an axial plane of said turbine. Fig. 3 is a horizontal section and plan view on line 3—3 of Fig. 2. Fig. 4 is a plan view of a detail of construction 60 of the turbine.

The same reference characters indicate the same parts in all the figures.

I will first describe the details of construction of the embodiment of my invention herein illustrated and then explain the principles involved therein.

In the drawings 10 represents a base plate which forms a support for the entire turbine, when the same is designed to be operated with its axis vertical, as here shown. Rising from the base plate are a series of vertical guide vanes 11, the arrangement of which is best shown in Fig. 3, which have a circular arrangement about the axis of the 70 turbine and are tangential to the circumference of the entrance portion of the rotor or wheel of the turbine, as will presently be more fully explained. On the upper ends of the guide vanes rests a ring 12 of which 75 the inner and outer circumferences define approximately the limits of the inner and outer edges of the guide vanes. Rising from the ring 12 is a shell 13, preferably cylindrical in form, which incloses the support 80 for the rotor or wheel, the throttling gate, and the mechanism for operating the gate. Resting upon and suitably secured to the top of the shell 13 is a top casing 14, which 85 may be removed when necessary to give access to the interior of the shell. Preferably the base plate, guides 11, ring 12, and shell 13 are all integrally connected together, being made as integral parts of a single casting. While the principles according to 90 which the potential energy in the water is converted into work do not depend upon having the parts thus made as a single casting, and the objects of the invention in these respects would be secured as well by making some, at least, of these parts separate 95 from others and securing them together in a sufficiently rigid manner, yet as a feature of construction which results in economies of manufacture and in greater strength and 100 accuracy of the complete turbine, I consider that the making of these parts in one piece 105 is a matter of great, although minor importance.

At an intermediate elevation within the 110

shell 13 is a flange or lip 15 whereon rests a plate 16 having a bearing sleeve 17 and formed with a circular rib 18. Fitting against the under surface of the plate 16 5 and against the outside of the rib 18 is a flange 19 which forms part of a cylindrical member 20 which has a bottom 21 and may be called, both from its shape and on account of one of the uses which it serves, a 10 cup. Said member, or cup, is also a hanger and support for the thrust bearing by which the downward pressure of the water wheel or rotor is sustained. In the center of the bottom plate 21 of the cup is a boss 22 15 having a bore in alignment with the bearing or boss 17, and with an aperture in the end wall of the top casing 14.

A shaft 23 passes through the bosses 17 and 22, and through the central opening in 20 the end wall of the top casing 14 and through a stuffing box 24 fixed upon said end wall coaxial with the opening therein. The shaft thus has a bearing at three points and is accurately and reliably held thereby in the 25 proper position and alignment. Said shaft has fixed upon its lower end a water wheel or rotor 25, which is supported by the shaft in such a position as to receive water flowing between the guide vanes 11 and which is 30 rotated by said water and drives the shaft. I will describe the wheel more in detail at a later point.

The weight of the wheel and shaft and of the water acting thereon is borne by an 35 antifriction thrust bearing shown in Fig. 2, composed of a series of balls 26, which rest and run upon a ball race 27 supported by a centering ring 28 on a stuffing box gland 29 held by the bottom 21 of the cup or hanger. 40 The upper ball race rests on the balls 26 and on the race 30 rests a cap or head 31, which is keyed to the shaft and is pressed upon by and underlies a shoulder 32 of the shaft. Thus it will be seen that the shoulder 32 45 supports the shaft and water wheel and is supported by the relatively frictionless ball bearing, so that the water wheel is retained at the proper level and is able to rotate with the minimum of frictional resistance 50 opposing its rotation. The bottom wall 21 of the cup, which directly supports the antifriction bearing is hung from the plate 16 by the walls of the cup and by strengthening and stiffening webs 33, and the plate 16 is 55 supported by the flange 15 which forms a part of the shell 13 and is supported upon the base plate 10. Thus not only the shell or casing but also the rotor and main shaft of the turbine are all mounted upon the 60 base plate 10 and the turbine is thus entirely self-contained. A function of the cup 20 is to contain oil to a sufficient depth to cover the ball bearing; whereby the latter is constantly lubricated and the friction and wear 65 upon the same reduced to the smallest pos-

sible amount. I consider that the amount of wear on the bearing would be so slight that it may run for years without requiring any attention and without causing or permitting the wheel to be lowered by any appreciable amount. Thus the thrust bearing may be located in a position where it cannot be tampered with, where it may run in a body of oil, and where it is guarded against danger of being accidentally struck and disarranged by objects carried with the flowing water.

In order that the oil may not escape from the cup and that water may not rise through the bearing in the bottom of the cup, I have provided a stuffing box in the boss 22, in which there is packing 34 compressed by the gland 29. Another stuffing box is pro-

vided in the bearing 17 comprising packing 35 and a gland 36, and in addition, a pack- 85 ing washer may be interposed between the flange 19 and the plate 16 so as to prevent water which may fill the compartment of the shell above the plate 16 from working into the cup 20. It will be seen that the 90

cup 20 provides a chamber in which the thrust bearing is contained, which chamber is entirely closed so that no water can possibly enter it, and from which the oil sup- 95

plied to lubricate the thrust bearing can not escape. The shell or cup 20 provides also a bearing for the rotor and a guide for the gate provided to shut off the water from the 100

rotor. The first mentioned function is pro- 105

vided by a peripheral lip 37 at the lower edge of the cup which receives the upper circumferential edge or lip 38 of the rotor. For guiding the gate, which is a cylindrical 110

member 39 surrounding the cup 20, the sides of said cup are made cylindrical on the exterior and finished so that the gate, which is finished on its interior has a smooth sliding fit. At two points, more or less, in the gate are longitudinal ribs 40 which slide in longi-

tudinal grooves or keyways in the outer sur- 115

face of the cup 20, thereby preventing the gate from rotating. Said gate bears externally on the inner circumference of the ring 12, with which it makes a sufficiently tight 120

sliding fit to prevent any material upward flow of water, and which is adapted, when lowered, to rest against an inwardly project- 125

ing shelf 41 on the base plate 10, which ex- 130

ends beyond the inner limits of the guide vanes 11 toward the axis of the turbine. The position of the gate when closed is indicated by the dotted lines 42 in Fig. 2.

For raising and lowering the gate I pro- 135

vide racks 43 connected at diametrically op-

posite points to the gate by means of pins 144. The racks extend upwardly through

slots in the plate 16, outside of the area of

contact between such plate and the flange 19.

A transverse shaft 45 passes across the chamber or space above the plate 16, being 150

held in bearings 46 so that it may rotate, and carries pinions 47 which mesh with the racks 43. The opposite ends of the shaft extend through the opposite sides of the top casing 14, and on one end is fixed a driving pinion 48, while the other end carries a counter-balancing device 49. The pinion 48 is driven by an intermeshing pinion 52 fixed to a shaft 53, which has a bearing in a bracket 54 fixed to the top of the turbine shell, and the lower end of which has a step bearing 55 rising from the sleeve 56 on the side of the shell through which the shaft 45 extends. Another shaft 57 parallel to the shaft 45 passes across the backs of the racks 43 and carries wheels 58 (shown in Fig. 4) having flanges 59, each of which wheels engages the rear face and edges of one of the racks to prevent the same from springing away from and out of mesh with the co-operating driving pinion 47. The shafts 45 and 57 are in substantially the same horizontal plane and are mounted in connected bearings, which are supported on pads 60 rising from the plate 16. Said plate and the bearing boss 17 are stiffened by ribs 61 on the upper side and webs 62 on the lower side, arranged as clearly shown in Fig. 2.

It is practically impossible, or at least difficult, to prevent water from entering the upper chamber of the casing in which the racks 43 and driving gearing are contained, and therefore the walls of this chamber are provided with apertures 63 to permit free ingress and egress of water and thereby avoid obstruction to the free movement of the racks in raising and lowering the gate. In addition there are hand-holes 64 in the end wall of the top casing 14, the limits of which are indicated by dotted lines in Fig. 2, so that access to the interior of this chamber may be had when necessary. It will be seen that the mechanism described provides a very simple and easily operated means for quickly raising and lowering the gate, for starting and shutting down the turbine, respectively. The counterbalancing device practically sustains the weight of the gate and racks, retaining them in the elevated position and making unnecessary the exertion of any greater mechanical force in raising the gate than is necessary to overcome the comparatively slight frictional resistance opposing its motion.

Important improvements by which I am enabled to secure great advantages in production of rapid motion and development of power reside in the construction of the wheel, or rotor, and the guide vanes 11. It is to be understood that the turbine, when in use, is so set in a flume or penstock that the only escape for the water therefrom to the tail race is through the guide vanes and the wheel. The water above the base plate 10 entirely surrounds the turbine, and in

order to escape past the base plate must flow through the channels or water ways provided between the guide vanes and the buckets of the wheel. The wheel is provided with a certain number of buckets, 70 such number being dependent upon the conditions of use, that is, the supply and head of water available, the power to be developed and the speed at which the wheel is to be run. In the machine illustrated the 75 number of such buckets is twelve, although I do not restrict the invention to that number and reserve the right to provide more or fewer as conditions require. The buckets, or blades, of the wheel are designated by the 80 character 65. They form the lateral partitions between the adjacent water ways, and the abutments whereon the water acts to impart motion to the wheel. The inner boundaries of the water ways are formed 85 by walls 67 and 68, the first of which extends upwardly and outwardly from the hub or central part of the wheel and the second of which extends downwardly and outwardly from the central part of the wheel. The 90 space between the buckets at the periphery of the wheel is entirely open between the base plate 10 and the ring 12, that is, between the upper and lower boundaries of the channels through which the water passes 95 in entering the wheel. The wheel has an outer wall 69 which surrounds the lower part of the wheel below the base plate and forms the outer boundaries of the water ways in that part of the wheel. The portions of the bucket 65 above the base plate are radial to the axis of the wheel, or approximately so, while below the base plate they are offset angularly around the axis of the wheel, the lower parts of the buckets 100 extending on gradual and smooth curves from the radial portions thereof backwardly in the opposite direction to that in which the wheel is adapted to run. The shape and formation of the water ways between the buckets is an important feature. In the entrance part of the water way, the rear boundary thereof formed by the wall 67 is curved on a line or surface corresponding to the curvature of water in falling 110 freely over a dam. This curve in its upper part has a relatively short radius and comes approximately tangent to the under surface of the ring 12. The radii of curvature become progressively and rapidly longer toward the lower part of the wall 67, until the point 70, near the level of the inner lip of the base plate, is reached. From this point the inner wall of the water way is more rapidly, but still smoothly and gradually curved, until it merges with the outer convex conical surface of the wheel 68, the surface elements of which extend on straight lines to the lower edge of such wall. Thereby the water entering the water ways of the 115

120

125

130

135

wheel is allowed and caused to change its direction downwardly in a manner corresponding to the natural and free fall of water, and is then discharged from the 5 wheel outwardly from the axis thereof to an extent corresponding to the free movement which would be given it by the centrifugal force of its rotary movement about the axis of the wheel. It is to be remembered that a stream of water passing 10 through any one water way is not turned back upon itself when the wheel is running in the intended efficient manner, that is, not deflected more than ninety degrees in a 15 vertical plane, but that in fact it is deflected through less than ninety degrees, because it is discharged from approximately the opposite side of the wheel from that at which it enters, the wheel being so designed 20 as to secure that result, as will be further described. The angular or spiral curvature of the lower portions of the buckets around the axis of the wheel is made of such an amount that the reaction of the falling 25 water thereon is sufficient, in connection with the impulse of the entering water acting against the radial upper parts of the buckets, to drive the wheel through approximately one hundred and eighty degrees during 30 the time required for any particle of water to pass entirely through the water way. The lateral offsetting about the axis of the wheel is indicated in Fig. 1 where enough of the outer wall 69 has been broken 35 away to show the edges of two of the buckets.

Fig. 3 shows the relation of the guide vanes 11 to the buckets at the entrance portion of the wheel. First, it should be noted 40 that all the vanes, and the opposite faces of each vane, are tangential to the circumference in which the outer edges of the wheel buckets lie. Next, it should be noted 45 that the number of vanes is twice as great as the number of buckets. Finally, that the edges of the vanes and buckets are so curved and beveled that the water does not strike any surfaces except those upon which it is intended to strike squarely, and that 50 such surfaces are bounded by sharp edges. The guides divide the entering water into jets which are directed tangentially to the revolving wheel and strike squarely against the buckets at the extreme outer edges there- 55 of where the impact will have the greatest and most beneficial effect. This effect is greatly enhanced by the provision of two guide vanes and the corresponding number of intermediate water channels for each 60 bucket and water way of the wheel. There- 65 by the wheel buckets are acted upon by a succession of distinct jets, each of which is no wider than is necessary to furnish a sufficient mass of water. If the number of vanes were less, for instance, and if there

were only as many vanes as buckets, the stream of water striking the buckets would in some positions of the bucket be unnecessarily wide, with consequent loss of possible effective leverage, and in other positions of 70 the bucket the same jet of water might act upon two buckets, with the result of splitting the jet, and causing churning and eddying of the water with loss of efficiency. In my turbine the compact jets strike close to 75 the edges of the buckets where they are caused to act with the greatest leverage, and the jets are made distinct from one another and of such slight width by intermediate 80 guide vanes that they are not broken up and their energy dissipated on account of being only partly intercepted by the buckets 85 against which they strike. It will be noticed that there is an intervening circular space of considerable width between the 85 outer edges of the buckets and the inner edges of the vanes. This space is necessary to admit the gate, and it is made by design wider than is necessary merely for that purpose. With my arrangement of 90 vanes the jets are able to cross such space and strike the buckets properly being thence deflected into the water ways of the wheel, without being broken up and caused to fall 95 ineffectively into this intermediate space, although if the number of vanes were materially less in proportion to the number of buckets shown, a considerable amount of the water would be thus scattered and thrown into this space. Another virtue of 100 the relatively large number of guide vanes is that they act as a guard to prevent the entrance into the wheel of solid objects flowing with the water having large enough dimensions to become caught in the wheel. 105 Any objects small enough to pass between the guide vanes are also small enough to pass through the water ways of the wheel without being caught. The front edges on the rear sides of the guide vanes are beveled at 11^a and the inner edges at the front side thereof are beveled at 11^b. Similarly the outer edges of the buckets on their rear faces are beveled at 65^a. When the water first 110 encounters the guide vanes it strikes sharp edges and smooth surfaces, and when it leaves the veins it travels over smooth surfaces and leaves sharp edges. Then when the water strikes the front sides of the wheel buckets, it 115 strikes against flat surfaces which are bounded by sharp edges, there being no abrupt end faces of appreciable width on the buckets to deflect and break up the jets of water. Thus the formation of eddies and counter 120 currents in the water is prevented. The inner walls of the water ways merge with the surfaces of the buckets on smooth curves as indicated in Fig. 3, this being also for the same purpose.

From Fig. 2 it appears that the under 125

surface of the ring 12 is convex and that the upper face of the base plate 10 is also convex and rises from the outer edges of the guide veins 11 to the inner edges thereof. These surfaces of the ring 12 and base plate, respectively, form the upper and lower boundaries of the channels through which the water is directed to the wheel. They conform to the contraction which takes place 5 in a jet of water flowing through an orifice and by their curvature cause the jets which leave the inner limits of the vanes to issue without spattering or dripping.

It is an entirely new feature so far as I 10 am aware to make the lower boundary of the passages between guide vanes to a turbine convex and rising from the entrance to the discharge ends of such passages, and this feature is one which is of marked value 15 to my invention.

From the foregoing description of the 20 guide vanes and wheel it will be apparent that the entering water first acts by impulse upon the wheel, being so guided as to act 25 with the greatest possible effect; and that after striking the buckets the water travels through the water ways, is deflected downwardly by the inner walls thereof, and then further impels the wheel by reaction against 30 the offset lower portions of the buckets, finally being discharged downwardly and outwardly from the wheel at the opposite side thereof from its point of entrance. The 35 wheel and guides have been especially made in all sizes to offer the least resistance and facilitate the freest and smoothest possible flow of the water. In this respect the peculiar curve of the inner walls 67 of the 40 water ways and the outward slant of the lower walls 68 thereof is important. The deflection from horizontal to vertical flow of the water is carried out according to the natural fall of water, and the discharge is directed outwardly in such a way that the 45 maximum reaction of the water occurs at a wide distance from the axis where the leverage is great. Finally the outward discharge enables the water to leave the wheel under residual momentum substantially equal to 50 that due to centrifugal force, and it therefore leaves the wheel freely, without shock and without back pressure. That is, the residual momentum of the water is of such a quantity that none of the energy given to 55 the wheel is expended in discharging the water.

Another feature of the invention consists in supplying air inside of the cone of discharging water at a sufficient rate to destroy 60 the vacuum which the water has a tendency to form by reason of its outward movement from the wheel. For this purpose I provide a longitudinal passage 71 which extends through the shaft 23 from a point above the 65 surface of the water supply to a point at or

near the bottom end of the shaft within the space inclosed by the inner bottom wall 68. Without the provision of means of supplying air to the under side of the wheel, the outwardly flowing water would create a 70 vacuum beneath the wheel which would have the effect of drawing the falling water inwardly after it leaves the wheel, and preventing its free and unimpeded discharge, thereby diminishing the efficiency of the 75 wheel. The lower end of the shaft passes entirely through the hub portion of the wheel, being tapered to fit the internally tapered bore thereof and having a shoulder 80 72 which abuts against the upper end of said hub. The lower end of the shaft is threaded and receives a holding nut 73 which clamps the wheel against the shoulder 72, and a lock nut 74. A key may be passed through the 85 shaft.

The outer wall 69 of the wheel is also so made as to give to the wheel the functions and capabilities of a fly wheel. It is made massive, having a greater quantity of material than is necessary for strength alone, 90 and the mass of material which it contains is so distributed as to have its greatest thickness at the bottom of the wheel where the diameter is greatest. Thus the wall 69 provides a mass of heavy metal concentrated at 95 the periphery of the wheel where it may best serve the purpose of absorbing energy and delivering such energy automatically when required to overcome variations in resistance to the motion of the wheel and to maintain 100 such motion uniform.

Another important feature of the invention is that the entire wheel 25 with its hub, buckets, and walls 67, 68, and 69 is made as a single integral casting. This mode of construction besides providing the greatest possible strength and rigidity, has another effect of even greater importance, in that it enables the production of a great number of 105 wheels absolutely alike, making it possible to duplicate a correctly designed wheel, and avoiding any possibility of some of the wheels made according to certain designs failing to meet their designed requirements. I understand that the makers of all the commercial turbines have had difficulty in securing uniformity of product, which is due largely to the fact that such turbines are built up of a number of parts, and that the slightest error in the setting up of the 110 buckets may have a serious vitiating effect in the performance of the turbine. There is no such possibility with a turbine constructed according to my invention, because any 115 number of wheels may be cast from the same patterns, and when the patterns have been correctly made all of the wheels produced therefrom will be absolutely uniform and correct.

I have already mentioned that I do not in- 120 125 130

tend this particular description to be considered as limiting my invention to water turbines. I desire to say further that I contemplate adapting the same principles in modification of the turbine adapted to be driven by steam and other motive fluids, and that I also contemplate modifying the machine, also within the principles of the invention so that the same may be operated as a pump.

What I claim and desire to secure by Letters Patent is:

1. A turbine comprising a base, a circular series of guide vanes mounted upon said base and having guiding channels between them, a shell or casing rising from said guide vanes, a shaft centrally arranged within said shell, a wheel or rotor fixed upon said shaft and rotatably arranged within the series of guide vanes, having buckets and intermediate channels to receive the fluid issuing from said vanes, and a thrust bearing contained within and supported by said shell and disposed so as to sustain the wheel against the thrust of the working fluid and against lateral shifting.
2. A turbine comprising a casing or shell having a base and a series of guide vanes and intermediate water channels in its lower portion, a wheel having buckets and water ways arranged to rotate in the space bounded by said guide vanes, a shaft to which said wheel is secured and by which it is carried and a thrust bearing supported in said casing above and close to the wheel and engaged with the shaft, to support the weight of the wheel and shaft and the water acting thereon.
3. A turbine comprising a casing or shell having a base and a series of guide vanes and intermediate water channels in its lower portion, a wheel having buckets and water ways arranged to rotate in the space bounded by said guide vanes, a shaft to which said wheel is secured and by which it is carried and a thrust bearing supported in said casing above the wheel and engaged with the shaft, said casing having an inner chamber inclosing the thrust bearing and adapted to contain oil.
4. A turbine comprising a casing or shell having a base and a series of guide vanes and intermediate water channels in its lower portion, a wheel having buckets and water ways arranged to rotate in the space bounded by said guide vanes, a shaft to which said wheel is secured and by which it is carried and a thrust bearing supported in said casing above the wheel and engaged with the shaft, said casing having an inner chamber inclosing the thrust bearing and adapted to contain oil, and means for preventing entrance of water to said oil-containing inner chamber.
5. A turbine comprising in its construc-

tion, a casing having in its lower portion a circularly arranged series of guide vanes and intermediate water channels, and having an open space within said series of vanes, and a water wheel contained rotatably in said open space, a shaft secured to said water wheel and passing through said casing, a gate arranged intermediate said guide vanes and the portion of the water wheel surrounded by them, said gate being cylindrical and adapted to be projected between the vanes and wheel and withdrawn, and a gate guiding member mounted in the casing above the wheel having an external surface arranged to be embraced by and to guide the gate, and having a bottom surrounding the shaft, and a thrust bearing supported by the bottom of said member for supporting the wheel and shaft, said member being internally formed as a chamber adapted to contain lubricant.

6. In a turbine, the combination with a casing including guide vanes and intermediate water channels in its lower portion, a wheel located within the space bounded by said guide vanes and adapted to rotate therein, a shaft passing through said casing, a member constituting a combined bearing support, oil container, and gate guide secured within said casing to surround the shaft above the wheel, a thrust bearing mounted within said member and engaged with said shaft to prevent endwise movement thereof and displacement of the wheel, and a cylindrical gate surrounding said member and arranged thereon to slide endwise between the wheel and guide vanes.

7. In a turbine, the combination with a wheel and a casing within which said wheel is mounted, and an antifriction thrust bearing contained within said casing above the wheel in such proximity thereto as to prevent sidewise displacement of the wheel.

8. In a turbine, the combination with a wheel and a casing within which said wheel is mounted, an antifriction thrust bearing contained within said casing above the wheel, and means for excluding water from said bearing.

9. In a turbine, a casing comprising a shell, a member supported within said shell formed externally as a gate guide and internally as a thrust bearing support, a thrust-bearing mounted on and within said member, a gate surrounding said member and adapted to move endwise thereon, racks connected to said gate at opposite sides thereof, pinions meshing with said racks, a shaft to which said pinions are connected passing outside of the shell and gearing arranged to drive the shaft for opening and closing the gate.

10. In a turbine, a wheel or rotor having buckets or blades and intermediate channels for the flow of working fluid, the buckets ad-

5 jacent to the entrance ends of the channels being located substantially in planes radial to the axis of the wheel, and their inner walls being inclined toward the axis on a concave curve of which the curvature becomes continuously flatter as it approaches the axis, the lower portions of the buckets being offset angularly about the axis of the wheel and the inner walls of the water ways 10 inclosed within these portions of the buckets being inclined away from the axis of the wheel.

11. In a turbine, a water wheel or rotor having buckets and intermediate water 15 ways, the buckets adjacent one end of the wheel being in substantially radial planes and the inner limits of the water ways between these portions of the buckets being bounded by curves which approach the axis 20 of the wheel and of which the radii of curvature grow progressively longer as they approach the axis, the parts of the buckets

adjacent to the opposite end of the wheel being offset angularly around the wheel from the radial parts thereof, and the inner 25 walls of these parts of the water ways being outwardly inclined from the axis.

12. In an axial flow turbine, a wheel having water ways of which the entrance portions are in the upper part of the wheel and 30 are substantially radial thereto and the discharge portions are in the lower part of the wheel and are offset so as partially to surround the axis thereof, the inner walls of the entrance portions of the water ways being 35 curved correspondingly to the curve assumed by the surface of a stream of water in a natural fall.

In testimony whereof I have affixed my signature, in presence of two witnesses.

DANA EDSON PERKINS.
